UNITED STATES PATENT OFFICE.

JAMES P. COUGHLIN, OF CHICAGO, ILLINOIS.

ADVERTISING DEVICE.

973,003.

Specification of Letters Patent. Patented Oct. 18, 1910.

Application filed December 6, 1909. Serial No. 531,604.

To all whom it may concern:

Be it known that I, JAMES P. COUGHLIN, a citizen of the United States, residing at Chicago, in the county of Cook and State of Illinois, have invented certain new and useful Improvements in Advertising Devices; and I do declare the following to be a full, clear, and exact description of the invention, such as will enable others skilled in the art to which it appertains to make and use the same.

This invention relates to improvements in automatic stereopticon advertising devices.

One object of the invention is to improve and simplify the construction and arrangement of the operating mechanism of devices of this character thereby increasing the efficiency and reducing the cost of manufacturing the same.

Another object is to provide an advertising device of this kind which may be constructed for use indoors or made on a large scale for outside use.

With the foregoing and other objects in view, the invention consists of certain novel features of construction, combination and arrangement of parts, as will be more fully described and particularly pointed out in the appended claim.

In the accompanying drawings, Figure 1 is a side view of an advertising device constructed in accordance with the invention, one side of the casing being removed; Fig. 2 is an enlarged detail front elevation, partly in section; Fig. 3 is a vertical section on the line 3—3 of Fig. 1; Fig. 4 is a horizontal section on the line 4—4 of Fig. 1.

In the embodiment of the invention I provide a casing 1 which may be of any suitable size and shape and provided with suitable doors and openings whereby access may be had to the operating mechanism arranged therein. Arranged in the casing 1 is a supporting frame comprising a front plate 2 and a rear plate 3 which are held together in spaced relation by shouldered bolts 4 or other suitable connecting devices. Revolvably mounted in the plates 2 and 3 of the frame is a wheel supporting and operating shaft 5 the forward end of which projects through the front plate 2 and has fixedly mounted thereon a slide carrying wheel 6, in the outer portion of which are arranged slide holding devices of any suitable construction with which are adapted to be engaged the slides or transparencies 7 which

contain the advertising or other matter to be displayed by the machine. On the shaft 5 adjacent to the inner side of the plate 2 of the frame is a ratchet gear 8 while loosely mounted on the shaft 5 adjacent to said gear is a bell crank lever 9 on one arm of which is pivotally mounted a pawl 10 which is adapted to engage the teeth of the ratchet gear 8 and to turn the latter together with the shaft 5 and wheel 6 through a predetermined distance. The other arm of the bell crank lever 9 is connected by a pitman rod 11 to a crank disk or eccentric 12 which is fixedly mounted on a counter shaft 13, suitably mounted between the plates 2 and 3 of the supporting frame. When the shaft 13 is turned in the proper direction, the crank disk or eccentric 12 will be operated and the movement thereof imparted to the bell crank lever and the pawl 10 to operate the ratchet gear 8 in the manner described.

Any suitable means may be employed for imparting an intermittent movement to the shaft 13 and the part operated thereby. Said mechanism is here shown and preferably comprises a spur gear pinion 14 fixedly mounted on the shaft 13 and which is adapted to be engaged by a toothed segment 15 fixedly mounted on a shaft 16 which is pivotally mounted between the plates 2 and 3 and has fixed thereon one member of operating and speed decreasing gears 17, mounted on suitable shafts journaled between the plates 2 and 3 as shown. The train of gears 17 are driven by a pulley 18 connected by a belt 19 to a suitable motor 20 arranged in the casing 1.

Revolvably mounted in any suitable manner in the upper portion of the supporting frame and in the rear of the slide carrying wheel 6 is a shutter 21 comprising a disk in one side of which is formed a notch 22. On the shaft of the shutter or otherwise fixedly connected thereto is a sprocket pinion 23 which is connected by a sprocket chain 24 to a sprocket pinion 25 on the shaft 13 of the operating mechanism, whereby motion is imparted to the shutter to turn the same at the proper speed.

On the bottom of the casing 1 is arranged a pair of horizontal longitudinally disposed guide or track bars 26 with which are slidably connected the lower ends of an adjustable lens supporting frame 27 on the upper end of which and directly in line with the uppermost slides in the wheel 6 is secured

the projecting lens 28, whereby the matter contained on the slides is projected and thrown on to a suitable screen provided to receive the same. Secured by a suitable bracket 29 arranged on the rear plate 3 of the supporting frame is a condensing lens 30 in the rear of which is arranged a lamp house or box 31, which contains the light producing mechanism which light is thrown through the lenses and slides by suitable reflectors in any suitable manner:

By means of the operating mechanism herein shown and described, the slide carrying wheel has an intermittent movement so that the advertising matter on one of the slides will be exposed for a certain period of time and the wheel then turned to bring the next slide in an operative position. The movement of the shutter is so timed and regulated that when the slide carrying wheel is moving to change the position of the slides, the shutter will be between the light and the slide thereby cutting off the view or projection of the matter on the slide while the change is being made.

From the foregoing description taken in connection with the accompanying drawings, the construction and operation of the invention will be readily understood without requiring a more extended explanation.

Various changes in the form, proportion

and the minor details of construction may be resorted to without departing from the principle or sacrificing any of the advantages of this invention as defined in the appended 35 claim.

Having thus described my invention, what I claim is:—

In an advertising device of the character described, a supporting frame, a slide carrying wheel revolvably mounted thereon, a pawl and ratchet gear connected with said wheel, a cam operating disk connected with said pawl and ratchet mechanism, an intermittent driving mechanism to periodically 45 turn said cam, a train of speed reducing gears operably connected with said intermittent driving mechanism, a motor operably connected to said train of gears, lenses arranged in suitable position to project the 50 matter contained on the slides arranged in said wheel, means whereby light is thrown through said slides and lenses, and a shutter to cut off said light when the wheel is turning to change the position of the slide. 55

In testimony whereof I have hereunto set my hand in presence of two subscribing witnesses.

JAMES P. COUGHLIN.
